CLAIM

The ornamental design for a connector protector, as shown and described.

DESCRIPTION

FIG. 1 is a top perspective view of the connector protector showing my new design;

FIG. 2 is a front view of the connector protector; and

FIG. 3 is a cross sectional view taken along line 2—2 of FIG. 2 herein; the cord shown is for illustrative purposes only and forms no part of the claimed design.

FIG. 4 is a back view; the cord shown is for illustrative purposes and forms no part of the claimed design; and,

FIG. 5 is a cross section view from the end view; the outlet shown is for illustrative purposes only and forms no part of the claimed design.
